ABSTRACT

A Differential Phase Shifter for operating at a center operating frequency is disclosed which includes a transmission line and a pair of shorting stubs attached thereto spaced a quarter wavelength apart at the center operating frequency. Each of the stubs are shorted at a distance greater than a quarter of a wavelength at the center operating frequency from the transmission line. A diode susceptible of being turned on or off is located on each of the stubs at a point less than a quarter of a wavelength from the main transmission line. The disclosure explains how to select the impedance values for the transmission line and the two stubs, as well as the spacing of the shorts and the diodes.

SHUNT LOADED LINE PHASE SHIFTER**FIELD OF THE INVENTION**

This invention relates to a differential phase shifter and, particularly, to a shunt loaded differential phase shifter.

BACKGROUND OF THE INVENTION

Numerous applications exist in which circuitry is required for differentially phase shifting a signal in response to a control signal. One particular use for a differential phase shifter is in phased array radars.

In the March, 1965 edition of IEEE Transactions on MTT, Vol. MTT-13, No. 2, an article entitled High Power, p-i-n Diode Controlled, Microwave Transmission Phase Shifters by White, disclosed a differential phase shifter in which a main transmission line has two shorting stubs attached thereto spaced from each other by 90° at a center operating frequency. In the White disclosure, a short is applied to each of the stubs at symmetrical points with respect to a point 90° from the main transmission line at the center operating frequency. In each instance, the short closest to the main transmission line is selectively removable.

The White phase shifter is quite inexpensive to build and serves quite well for small differential phase shifts. As the phase shift desired increases, the input admittance of the main transmission line begins to take on a large imaginary component mismatching the differential phase shifter from the driving source. Furthermore, as the phase state changes, that is, as the short is applied to either of the points symmetrical about a point 90° from the main transmission line, the sign of this imaginary component changes, making it impossible to match the input admittance for both phase states. It has been found that even for small differential phase shifts a small imaginary component is present in the input admittance of the main transmission line.

Therefore, it is an object of this invention to provide a new and improved differential phase shifter.

It is further object of this invention to provide a new and improved differential phase shifter which has a real input admittance which is independent of the phase state.

It is a further object of this invention to provide a known improved differential phase shifter with a configuration which can provide differential phase shifts of substantial angles without introducing imaginary terms into the input admittance thereof.

BRIEF DESCRIPTION OF THE INVENTION

With these and other objects in view, the present invention contemplates a differential phase shifter having a center operating frequency and including a main transmission line having a characteristic admittance of Y_0 , first and second shunt transmission line stubs having characteristic admittances of Y_1 , and Y_2 , respectively, each of the shunt transmission line stubs have first ends thereof connected to the main transmission line at locations spaced 90° from each other. Each of the shunt transmission lines are provided with a device for selectively shorting the same at a location spaced from the respective first end thereof by a distance of θ_1 and θ_2 , respectively, at the center operating frequency, while a short is supplied on each of the shunt transmission line stubs at a location spaced from the respective first ends thereof by a distance of $(\theta_1 + 2\phi_1)$ and $(\theta_2 +$

$2\phi_2)$ where $(\theta_1 + \phi_1)$ and $(\theta_2 + \phi_2)$ are 90° at the center operating frequency; and the following relationship is satisfied:

$$Y_1 \text{Cot}\theta_1/Y_0 = Y_2 \text{Cot}\theta_2/Y_0/[1 + (Y_2^2 \text{Cot}^2\theta_2/Y_0^2)]$$

In the preferred embodiment, the device for selectively shorting the first and second shunt transmission line stubs include a diode and a bias network responsive to control signal for passing current through the 10 diodes.

DESCRIPTION OF THE DRAWING

For a more complete understanding of the invention, reference should be made to the following detailed description and drawing in which the sole FIGURE shows in schematic form a differential phase shifter embodying the principles of this invention.

DETAILED DESCRIPTION OF THE INVENTION

Referring now to the sole FIGURE, there is seen a differential phase shifter 10 for operation at a predetermined center operating frequency which includes a main transmission line 11, having a characteristic admittance of Y_0 terminated with a resistor 12 having an admittance of Y_0 . A first shunt transmission line stub 13 which has a characteristic admittance of Y_1 has a first end 14 connected to the main transmission line 11. A diode 16 has its cathode connected to the first shunt transmission line stub 13 at a point 17 spaced from the first end thereof 14 by a distance of θ_1 at the center operating frequency. A signal responsive bias network 18 is connected to the diode 16 by leads 19 and 21 to selectively pass current through the diode 16 in response to a control signal applied on a lead 22.

The first shunt transmission line stub is shorted at a point 23 which is located a distance $(\theta_1 + 2\phi_1)$ from the point 14 at the center operating frequency, where $(\theta_1 + \phi_1)$ is 90° at the center operating frequency.

A second shunt transmission line stub 24 which has a characteristic admittance of Y_2 has a first end thereof 26 connected to the main transmission line 11 at a point located 90° from the first end of the first transmission line stub 13 at the center operating frequency. A diode 27 has its cathode connected to the second transmission line stub 24 at a point 28 which is spaced from the first end thereof 26 a distance of θ_2 at the center operating frequency. A bias network 29 is connected to the diode 27 by leads 31 and 32 to selectively pass current through the diode 27 in response to the control signal being applied to a lead 33. The leads 22 and 23 are connected to each other and a control signal is applied thereto by a lead 34 so that the bias networks 18 and 29 are actuated together.

The second shunt transmission line stub is shorted at a point 36 which is located a distance $(\theta_2 + 2\phi_2)$ from the first end thereof 26 at the center operating frequency, where $(\theta_2 + \phi_2)$ is 90° at the center of operating frequency.

In operation a signal is applied to the input 37 of the differential phase shifter 10. With no control signal applied to the lead 34, the signal appearing across the resistor 12 has a fixed phase. Application of a signal to the lead 34 causes the bias networks 18 and 29 to pass current through the diodes 16 and 27, shorting the first and second shunt transmission line stubs 13 and 24 at the points 17 and 28, causing a fixed differential phase shift in the signal appearing across the resistor 12. In

accordance with this invention, the proper selection of the impedances Y_1 and Y_2 and the distances θ_1 and θ_2 results in a real input impedance at the terminal 37 independent of phase state.

By forming an expression for the input admittance of the differential phase shifter 10 and setting the imaginary portion thereof equal to 0, it has been found that the input admittance of the differential phase shifter 10, will be real when:

$$Y_1 \operatorname{Cot} \theta_1 / Y_0 = Y_2 \operatorname{Cot} \theta_2 / Y_0 / [1 + (Y_2^2 \operatorname{Cot}^2 \theta_2 / Y_0^2)]$$

From the above expression it can be seen that the admittance of the lines 13 and 24 and/or the location of the diodes 16 and 27, can be altered in fixed relationship and still obtain a real input admittance for the differential phase shifter 10. In accordance with design considerations the location of the diodes 16 and 28 (and therefore the shorts 23 and 36) can be the same while the admittances of the shunt transmission line stubs 13 and 24 can be set to provide the real input admittance. On the other hand, if design considerations dictate, the admittances of the shunt transmission line stubs 13 and 24 can be held the same and the location of the diodes 16 and 27 can be set to accomplish the same result. In some instances both the admittances and diode locations can be adjusted to achieve the real input admittance as long as the relationship set forth above is met.

The value of Y_2 and θ_2 are determined by the total differential phase shift required. This relationship is given by

$$\phi = 2 \tan^{-1} (Y_2 / Y_0) \operatorname{cot} \theta_2$$

While this invention has been described with respect to a particular embodiment thereof, numerous other embodiments will become obvious to those of ordinary skill in the art in light thereof.

What is claimed is:

1. A differential phase shifter having a center operating frequency and including:
  - a main transmission line having a characteristic admittance of Y_0 ;
  - a first shunt transmission line stub having a characteristic admittance of Y_1 ; said first shunt transmission line stub having a first end connected to said main transmission line at a predetermined location;
  - means for selectively shorting said first shunt transmission line stub at a location spaced from said first end thereof by a distance of θ_1 at said center operating frequency;
  - means for shorting said first shunt transmission line stub at a location spaced from said first end thereof

5. by a distance of $(\theta_1 + 2\phi_1)$ where $(\theta_1 + \phi_1)$ is 90° at said center operating frequency;
6. a second shunt transmission line stub having a characteristic admittance of Y_2 ; said second shunt transmission line stub having a first end connected to said main transmission line at a location spaced from said predetermined location by 90° at said center operating frequency;
7. means for selectively shorting said second shunt transmission line stub at a location spaced from said first end thereof by a distance of θ_2 at said center operating frequency.
8. means for shorting said second shunt transmission line stub at a location spaced from said first end thereof by a distance of $(\theta_2 + 2\phi_2)$, where $\theta_2 + \phi_2$ is 90° at said center operating frequency; and the following relationship is satisfied:

$$Y_1 \operatorname{Cot} \theta_1 / Y_0 = Y_2 \operatorname{Cot} \theta_2 / Y_0 / [1 + (Y_2^2 \operatorname{Cot}^2 \theta_2 / Y_0^2)]$$
9. 2. The differential phase shifter as defined in claim 1 also including:
  - means for terminating said main transmission line in an admittance of Y_0 .
  - 3. The differential phase shifter as defined in claim 1 in which $\theta_1 = \theta_2$.
  - 4. The differential phase shifter as defined in claim 1 in which $Y_1 = Y_2$.
  - 5. The differential phase shifter as defined in claim 1 in which said means for selectively shorting said first shunt transmission line stub includes:
    - a first diode; and
    - a first bias network responsive to a control signal for passing current through said first diode.
  - 6. The differential phase shifter as defined in claim 5 in which said means for selectively shorting said second shunt transmission line stub includes:
    - a second diode; and
    - a second bias network responsive to said control signal for passing current through said second diode.
  - 7. The differential phase shifter as defined in claim 6 in which $\theta_1 = \theta_2$.
  - 8. The differential phase shifter as defined in claim 7 also including:
    - means for terminating said main transmission line in an admittance of Y_0 .
    - 9. The differential phase shifter as defined in claim 6 in which $Y_1 = Y_2$.
    - 10. The differential phase shifter as defined in claim 9 also including:
      - means for terminating said main transmission line in an admittance of Y_0 .
